UNITED STATES PATENT OFFICE.

DURO GUCA, OF CHICAGO, ILLINOIS.

DESIGN FOR A HINGE.

52,476.

Specification for Design. Patented Sept. 24, 1918.

Application filed May 14, 1917. Serial No. 168,575. Term of patent 3½ years.

To all whom it may concern:

Be it known that I, DURO GUCA, a citizen of the United States, residing in Chicago, in the county of Cook and State of Illinois, have invented a new, original, and ornamental Design for a Hinge, of which the following is a specification, reference being had to the accompanying drawing, forming part thereof.

Figure 1 is a side elevation of a hinge showing my new design;

Fig. 2 is an edge view of same, taken on line 2—2 of Fig. 1.

I claim:

The ornamental design for a hinge as shown.

In witness whereof, I have hereunto subscribed my name this 27th day of April, 1917.

DURO GUCA.
